UNITED STATES PATENT OFFICE.

SIDNEY A. RAGAN, OF NEW ORLEANS, LOUISIANA.

PAPER-PERFORATING MACHINE.

Application filed August 7, 1926. Serial No. 127,803.

This invention relates to an improved paper perforating machine of the kind to be used in conjunction with a piano, organ, or other keyboard instruments for perforating 5 paper for player piano rolls.

My principal object is to generally improve upon the paper perforating machine illustrated and claimed in Patent No. 1,558,504 granted to me on October 27th, 10 1925.

Briefly, in the patented device, a structure is shown which is in the form of an attachment for a musical instrument of the class described, this attachment embodying, 15 among other parts, a frame which includes a base over which the paper to be perforated is adapted to be passed. Mounted on this base is a vertically movable horizontally disposed bar carrying paper punching bars, 20 and there being latches for effecting a connection between the punching bars and the carrying bar therefor, together with key operated means for actuating the latches according to the particular key which is de- 25 pressed on the keyboard.

The present invention also embodies a base over which the paper to be perforated is adapted to pass, this being formed with openings with which the punch bars are aligned. These punch bars are carried by a horizontally disposed vertically movable bar member which is reciprocated by a novel eccentric structure. This is one improvement over the patented devices, and another im- 30 provement is the latch construction, together with the means for operating and guiding the latches.

A further feature of construction is the electric magnetic means for operating flexible elements which control the action of the latches in one direction.

Other objects and advantages will be mentioned and will become apparent from the following drawings.

In the accompanying drawings forming a part of this application and in which like numerals are employed to designate like parts throughout the same:—

Figure 1 is a perspective with portions 50 shown in section and elevation of a part of the structure showing the latch mechanism, operating means and clutch bar structure plainly,

Fig. 2 is a fragmentary view with por-

tions shown in section and elevation dis- 55 closing the frame structure,

Fig. 3 is a front elevation of one end portion of the structure,

Fig. 4 is a detail view of certain of the de- 60 tails.

Referring to the drawings in detail, it will be seen that the reference character 1 designates a part of the frame structure and the reference character 2 designates the base over which the paper to be perforated is 65 adapted to pass, suitable mechanism (not shown) being employed for moving the paper. At the center of the base are holes 3 to accommodate the lower prong equipped 70 ends of the punch bars 4. Above the openings 3 is a cross member 5 provided with holes for passage of the punch bars in order to guide these bars. Supported for vertical movement and in a horizontal plane over the guide member 5 is a carrier bar 6 for 75 the multiplicity of punch bars. Carried by the end portions of this carrier bar are brackets 7 provided with right angularly disposed end portions carrying rollers 8 in contact with cams or eccentrics 9 on a rotary 80 shaft 10 supported on the frame. As in the patent before referred to individual springs 11 are connected with the upper ends of the punch bars and the punch bars are slidably mounted on the carrier bar 6. Moreover, 85 the punch bars are provided with notches in which the inner ends of right angularly disposed latches 12 are seated. The latches are moved in a direction to disengage them from the notches by flattened springs 13 as shown 90 plainly in Fig. 2.

In the present construction, a shaft 14 is also rotatably mounted for oscillation on the frame at a point just above the guide member 5 as shown plainly in Fig. 2, and this 95 shaft is equipped with a multiplicity of disks 15 formed with notches 16 in their peripheral portions. As shown in Figs. 1 and 2, a disk is provided for each latch and a latch provided for each punch bar. Also, 100 as shown in Fig. 4, a pair of comb-like guide members 17 and 18 are employed for co-operation with the latches 12 and 15 respectively.

In other words, the lowermost guide mem- 105 bers shown in Figs. 2 and 4 cooperate with the latches and the upper ones cooperate with the peripheral portions of the disks.

Referring now to Fig. 1, it will be seen that a flexible element in the form of a wire or equivalent material 19, is connected with each disk and is passed through a guide 5 opening in another guide member 20 and upwardly and at its upper end is connected with the free end of a flexible armature carried by the upright 22. This armature cooperates with an electro-magnet 23 with 10 which the electric conductors 24 and 25 are connected. These conductors are in turn connected with a switch on a key on the keyboard in a manner not shown. There is an electric circuit including a magnet for each 15 key on the instrument.

The operation of the machine is as follows:—The paper to be perforated passes over the base plate between the apertured bar 3 and the guide member 5, and it is obvious 20 that when one of the punch bars comes down, it will perforate the paper. In order to control the particular bar to come into action, the electric circuit is brought into play. For instance, by depressing one of the keys 25 on the keyboard instrument with which the device is used, the electro-magnet 23 in that particular circuit is energized, thus moving the armature 21 upwardly and exerting a pull upon the adjustable element 19. In so 30 doing, the disk 15 is oscillated in a direction to exert a push upon the latch with which it cooperates.

Normally the latch is disengaged by the 35 spring 13, but when the disk is thus oscillated, it is pushed into the notch in the complementary punch bar, thus coupling the punch bar with the vertically movable carrier bar 6. The carrier bar is operated through the medium of the cam and roller construction shown in Fig. 2. When the 40 switch is opened, the circuit is broken and the parts assume their normal positions.

It is believed that by considering the description and connection with the drawings, 45 persons familiar with devices of this class will be able to obtain a clear understanding of the same. Therefore, a more lengthy description is thought unnecessary.

While the preferred embodiment of the 50 invention has been shown and described, it is to be understood that minor changes coming within the field of invention claimed, may be resorted to if desired.

Having thus described my invention, what I claim as new is:—

1. In a paper perforating machine of the class described, a frame, a base plate on said frame over which the paper to be perforated is adapted to be passed, said base plate formed with openings, punch bars supported for vertical movement through said openings, a latch cooperative with each punch bar and extending at right angles thereto, spring means for normally moving the latch to disengage it from its complementary punch bar, a shaft, disks mounted on said shaft, each disk having a notched portion in which one end of the latch is located, and means for oscillating the disk to move said latch in a direction against the tension of the spring to engage the latch with its punch bar. 65

2. In a paper perforating machine of the class described, a frame, a base plate over which the paper to be perforated is adapted to pass, said base plate being formed with openings, a carrier bar mounted for vertical movement upon the frame, a notched punch bar on said carrier bar, said punch bar being aligned with one of the openings in the base plate, a latch on said carrier bar extending at right angles from the punch bar and receivable at one end in the notch formed in the punch bar, a shaft disposed in parallelism with the carrier bar, a disk on the shaft, a notch in the peripheral portion of the disk in which the opposite end of the latch is received, spring means for moving the latch in one direction, and a flexible element connected with the disk for moving the latch in the opposite direction. 85

3. In a paper perforating machine of the class described, a supporting frame, a base plate on said frame, said base plate being provided with a multiplicity of openings over which the paper is adapted to pass, a horizontally disposed carrier bar, punch bars carried by said carrier bar and in alignment with the openings in the base plate, brackets on the carrier bar, rollers carried by the brackets, a shaft mounted for rotation on the frame above the carrier bar, and cams on said shaft cooperable with said rollers for moving said carrier bar downwardly. 90

In testimony whereof I affix my signature.

SIDNEY A. RAGAN.
